UNITED STATES PATENT OFFICE.

GEORGE A. WEBER, OF STAMFORD, CONNECTICUT, ASSIGNOR TO THE WEBER RAILWAY JOINT MFG. CO., OF NEW YORK, N. Y., A CORPORATION OF WEST VIRGINIA.

INSULATED JOINT FOR RAILROAD-RAIL SECTIONS.

SPECIFICATION forming part of Letters Patent No. 772,009, dated October 11, 1904.

Application filed June 4, 1901. Serial No. 63,125. (No model.)

To all whom it may concern:

Be it known that I, GEORGE A. WEBER, of Stamford, county of Fairfield, State of Connecticut, have invented a new and useful Improvement in Insulated Joints for Railroad-Rail Sections, of which the following is a specification.

This invention relates to insulated rail-joints; and its objects are to improve upon the construction of such joints and increase their strength and efficiency.

Further objects of the invention are to secure a firm splice between the rails with high insulating qualities.

Further objects of the invention will hereinafter appear; and to these ends the invention consists of an insulated joint for carrying out the above objects embodying the features of construction, combinations of elements, and arrangement of parts having the general mode of operation substantially as hereinafter fully described and claimed in this specification and shown in the accompanying drawings.

In the accompanying drawings, Figure 1 is a transverse section of a railroad-rail joint embodying my improvement. Fig. 2 is a top view of the same, partly in section. Fig. 3 is a transverse section of a railroad-rail joint embodying a modified form of joint. Fig. 4 is an elevation of one side of the last-named railroad-rail joint.

Similar letters of reference designate corresponding parts in all the figures.

Referring first to Figs. 1 and 2, A' A² designate two rail-sections arranged in line end to end. B' B² designate two angle-chairs each having a base b' and an upright or bolt-plate b², the two being preferably strengthened at the junction by an outside fillet or rib b³ and an inside fillet or rib b⁴. The bases of these angle-chairs are in line and almost reach each other. The uprights of these angle-chairs are on opposite sides of the rail-sections. C' C² designate bars or blocks of insulating material, preferably of vulcanized fiber, fitted against opposite sides of the webs of the rail-sections. Outside these bars are

filling-pieces D' D², preferably of metal and in the form of thimbles. E is a strip of insulating material, preferably vulcanized fiber, extending entirely over the bases of the angle-chairs. Preferably it extends up to the top of the uprights of those chairs; but it may stop short of extending to the tops of the uprights, and then washers E' will be arranged intermediate of the filling-pieces and the uprights of the angle-chairs. The feet of the rail-sections rest upon this strip of insulating material. Outside the uprights of the angle-chairs are washers F' F² of insulating material, preferably vulcanized fiber. Outside these washers are metal washers G' G². The angle-chairs B' B², the bars C' C², and the strip of insulating material E extend across the adjacent ends of the rail-sections A' A² and to a sufficient extent to form a strong joint. Bolts K secure the parts together, and they pass through the washers G' G² F' F², uprights of the angle-chairs B' B², thimbles D' D², the bars C' C², and the rail-sections A' A². Either the rail-sections are insulated from the bolts or the uprights of the angle-chairs are insulated from the bolts. Both of these insulations may, of course, be adopted. I have shown bushings L surrounding the bolts where they pass through the uprights of the angle-chairs. These bushings may advantageously extend through the washers F' F² G' G².

Turning now to Figs. 3 and 4, it will be seen that the joint is the same as that already described excepting only that the angle-chair B², with its appurtenances, and the thimbles D² are omitted. The bolt-washers G² in this modification bear directly upon the insulating-bar C² without the interposition of a metallic strap. The base of the angle-chair in this example of the invention is made wide enough to extend even beyond the feet of the rail-section.

It will be seen that in each example of my invention the bars C' C², of insulating material, are distinguishing features and that in each example of the invention there may be at least one angle-chair, while in Figs. 1 and

2 an opposite part in the form of a bolt-plate also lapping the end portions of the rail-sections is provided, for the bolt-plate of the second angle-chair in the example of the invention illustrated in Figs. 1 and 2 is an opposite part to the bolt-plate of the first angle-chair.

Obviously some features of this invention may be used without others and the invention 10 may be embodied in widely-varying forms.

Therefore, without limiting the invention to the constructions shown and described nor enumerating equivalents, I claim, and desire to secure by Letters Patent, the following:

15 1. The combination with adjacent rail-sections arranged end to end, of an angle-chair having a base and an upright or bolt-plate and lapping the end portions of the rail-sections, a bar of insulating material arranged 20 intermediate the rail-sections and said upright and adjacent to the sides of the webs of said rail-sections, metal filling-pieces between the upright of the angle-chair and the adjacent bar of insulating material, a part in the form 25 of a bolt-plate opposite the upright of the angle-chair arranged on the other side of the rail-sections, and bolts for securing the parts together.

2. The combination with adjacent rail-sections arranged end to end, of bars of insulating material arranged upon opposite sides of the webs of the rail-sections, an angle-chair having a base and an upright or bolt-plate and lapping the end portions of the rail-sections, metal filling-pieces between the upright 35 of the angle-chair and the adjacent bar of insulating material, a part in the form of a bolt-plate opposite the upright of the angle-chair arranged on the other side of the rail-sections, 40 and bolts for securing the parts together.

3. The combination with adjacent rail-sections arranged end to end, of bars of insulating material arranged upon opposite sides of the webs of the rail-sections, two opposite angle-chairs, each having a base and an upright or bolt-plate, and both lapping the end portions of the rail-sections, metal filling-pieces between the uprights of the angle-chairs and the bars of insulating material, and bolts for 45 securing the parts together.

4. An insulated rail-joint, comprising the rail ends, bars of insulating material arranged along the rail-webs at each side, a bolt-plate at one side of the joint, filling-pieces in the

form of thimbles on the bolts and arranged 55 between the bolt-plate and one of the said insulating-bars, and suitable insulation for preventing the electric continuity of the rails.

5. An insulated rail-joint, comprising the rail ends, bars of insulating material arranged 60 along the rail-webs at each side, a rail-chair having a base and an upright or bolt-plate, filling-pieces in the form of thimbles on the bolts and arranged between the upright of the chair and one of the insulating-bars, and suitable insulation for preventing the electric continuity 65 of the rails.

6. An insulated rail-joint, comprising the rails, an angle-chair having a base and an upright or bolt-plate, a bar of insulating material arranged 70 intermediate the rails and said upright, metallic filling means between the upright of the chair and the adjacent bar of insulating material, and a part opposite the upright of the angle-chair on the other side 75 of the rails, with bolts for securing the parts together, and suitable insulation for preventing the electric continuity of the rails.

7. An insulated rail-joint, comprising the rails, bars of insulating material arranged 80 upon opposite sides of the webs of the rail-sections, an angle-chair having a base and an upright or bolt-plate, metallic filling means 85 between the upright of the angle-chair and the adjacent bar of insulating material, a part opposite the upright of the angle-chair arranged on the other side of the rail-sections, bolts for securing the parts together, and suitable insulation for breaking the electric continuity 90 of the rails.

8. An insulated rail-joint, comprising the rails, bars of insulating material arranged upon opposite sides of the webs of the rail-sections, two opposite angle-chairs each having a base and an upright or bolt-plate, metallic filling means between the uprights of the angle-chairs and the bars of insulating material, bolts for securing the parts together, and suitable insulation for preventing electric communication 95 between the rails.

In testimony whereof I have signed my name to this specification in the presence of two subscribing witnesses.

GEORGE A. WEBER.
